CLAIM

The ornamental design for a patio screen shaver, as shown and described.

DESCRIPTION

FIG. 1 is a first perspective view of a patio screen shaver in accordance with the present invention;

FIG. 2 is a second perspective view thereof;

FIG. 3 is a third perspective view thereof;

FIG. 4 is a fourth perspective view thereof;

FIG. 5 is a fifth perspective view thereof;

FIG. 6 is a top view thereof;

FIG. 7 is a bottom view thereof;

FIG. 8 is a left side view thereof, shown in enlarged scale;

FIG. 9 is a right side view thereof, shown in enlarged scale;

FIG. 10 is a front view thereof; and,

FIG. 11 is a back view thereof.

The broken lines shown in the drawings represent portions of the patio screen shaver that form no part of the claimed design.
